UNITED STATES PATENT OFFICE.

FRITHEOF H. HOFFSTEDT, OF SOMERVILLE, MASSACHUSETTS, ASSIGNOR
OF ONE-HALF TO WILLIAM J. MARSH, OF ARLINGTON, MASSACHU-
SETTS.

ELECTROTYPE-PLATE HOLDER.

No. 802,288.

Specification of Letters Patent.

Patented Oct. 17, 1905.

Application filed December 26, 1903. Serial No. 186 540.

To all whom it may concern:

Be it known that I, FRITHEOF H. HOFF-
STEDT, a citizen of the United States, residing
at Somerville, in the county of Middlesex,

5 State of Massachusetts, have invented a cer-
tain new and useful Improvement in Elec-
trotype-Plate Holders, of which the following
is a specification, reference being had therein
to the accompanying drawings.

10 The invention has relation to the means
which is employed in the process of printing
for supporting electrotype and similar plates
and holding the same securely in position in
readiness for taking impressions therefrom.

15 At the present time there are in use devices
comprising, essentially, a supporting-plate,
termed a "block," upon which the electro-
type-plate or the like is laid, and catches or
clamps serving to secure the said plate to the

20 block, provision being made for shift and ad-
justment of the catches or clamps to accom-
modate the shape of the electrotype-plate
and the position in which such plate is placed
upon the block.

25 The general object of the invention is to
provide means for the foregoing purpose and
of the class referred to of novel and improved
character and construction. One special ob-
ject or aim of the invention is to provide a

30 construction which shall be less expensive to
make than those heretofore employed. An-
other is to enable the catches or clamps to be
applied to or removed from the block more
conveniently than heretofore and to be ad-

35 justed quickly into any position thereof
which is required in order to enable the same
properly to be engaged with the edge of an
electrotype-plate or the like of any shape and
occupying any desired position upon the

40 block.

An embodiment of the invention is illus-
trated in the accompanying drawings, in
which—

Figure 1 shows in plan a grooved block and
45 plate-holding clamps applied thereto, to-
gether with an electrotype-plate or the like
lying upon the said block and engaged by the
said clamps to hold it in place. Fig. 2 is a
50 view in transverse section on the plane indi-
cated by the dotted line 2 2 in Fig. 1. Fig. 3
is an isometric view of one of the members of
the block which is employed in connection

with a plate-clamp. Fig. 4 is a similar view
of the other member of the said block. Fig.
5 is a similar view of the catch or plate-engag- 55
ing member of a clamp.

Having reference to the drawings, in Figs.
1 and 2 an electrotype-plate is meant to be
represented at A, and at 1 is represented a
so-called "block," which in practice usually 60
is formed of metal, upon which the said plate
A is mounted for support in a printing-press.

The drawings show simply a plate A of ob-
long rectangular shape. It is of course well
understood that in practice the sizes, propor- 65
tions, and shapes of electrotype-plates and
the like vary greatly and that the size of the
block also varies in different cases. The
edges of the plate A are shown parallel with
those of the block; but it is well known that 70
in practice the position of the plate upon the
block may require to vary more or less. The
block 1 is formed with a series of grooves 2 2 in
one surface thereof parallel with one another
and extending across the plate at an angle to 75
the edges of the latter. In conformity with one
feature of the invention these grooves 2 2 are
formed with the sides or walls thereof also par-
allel with each other in the direction of the
thickness of the block 1—that is to say, verti- 80
cally—as shown best in the cross-sectional
representation. The plate-holding clamps
comprise, essentially, blocks which fit within
the said grooves 2 2 and are capable of being
adjusted lengthwise along the said grooves 85
into the required position, catches or plate-
engaging members to take against the edges
of the plate A, and means of forcing the
catches or plate-engaging members into firm
engagement with the edges of the said plate 90
A and also expanding the said blocks so as
to cause the sides of the same to bind against
the opposite parallel side walls of the grooves
and by frictional hold thereupon retain the
clamps and plate A securely in place. The 95
blocks may vary somewhat in form, propor-
tions, and construction. In the present em-
bodiment of the invention they comprise
each two members 3 and 4. The acting
faces 34 44 at the outer sides of the said 100
members are formed to be parallel with each
other in the direction of the height of the
block in the expanded condition of the block,
corresponding in this respect of parallelism

with the side walls of the groove 2, into which the block is placed. The faces 31 and 41 of the respective members make contact with each other. The said contacting surfaces are oblique or inclined, the obliquity or inclination being in a direction to spread the members so as to increase the width of the block when member 4 is moved upward relative to member 3 and to permit the block to contract in width when the member 4 is moved downward with reference to member 3. Provision is made for preventing end-wise displacement of member 4 relative to member 3. This may be effected variously. Preferably, though not necessarily, in all embodiments of the broader features of the invention, the member 3 is formed with end flanges 33 33, between which the member 4 enters. Separation of the two members of a block by excessive vertical movement of one member relative to the other is provided for in convenient manner. Such separation is herein prevented by forming the inner faces of the end flanges 33 33 to converge slightly toward each other in an upward direction, the member 4 being formed with a slight upward taper to adapt it to fit properly between such converging faces. Complete separation of the members transversely is prevented herein by forming the said surfaces to converge slightly toward each other in a horizontal direction toward their outer ends and forming the end surfaces of the member 4 with a corresponding convergence, although other means of accomplishing this result may be adopted in practice. The catch or plate-engaging member consists of a plate 5 of suitable proportions, which last may vary in practice according to requirements, the said catch or plate-engaging member having a flat lower surface and having also a beveled edge 51 to engage with the beveled edge *a* of the electrotype-plate A. The catch or plate-engaging member 5 is formed with a hole 52, passing vertically therethrough, through which hole is passed the stem of a screw 6, the said stem being entered into a screw-threaded hole 42, that is tapped vertically in the member 4 of the block, a countersink being formed in the upper surface of the catch around the hole 52 to receive the head of the screw.

In the use of the invention the screw 6 of each clamp is turned out of the block member 4 far enough to render the parts 3, 4, and 5 of each clamp loose relative to one another. The electrotype-plate A having been laid upon the block 1, the blocks of a suitable number of clamps are introduced into the grooves 2 2 and slid along within the said grooves into position to cause engagement of the clamps with the different edges of the plate A. On tightening the screws 6 6 the catches 5 5 will be drawn down into contact

with the edges of the plate A, and when such catches take a bearing against the said edges the screws will begin to draw the members 4 4 of the blocks up within the grooves 2 2. As the said members 4 4 are thus raised relative to the members 3 3 the action of the contacting oblique or inclined surfaces 31 41 will increase the width of the blocks so as to cause their outer surfaces to take a frictional hold against the parallel walls of the grooves 2 2. For the purpose of making a shift of a clamp in the direction of the length of the containing groove 2 therefor it is necessary simply to loosen the screw 6 of such clamp slightly, which will permit the member 4 to be caused to descend sufficiently relative to member 3 to enable the block to contract in width. This will render the block loose within the groove, and it may then be slid lengthwise of the latter in either direction. It will be apparent that adjustment of the clamps lengthwise of the grooves 2 2 to suit any required position of the plate A or any size or shape of such plate may be effected conveniently and expeditiously and without complete withdrawal of any of the screws 6 6 or the removal of any of the blocks from the grooves, the parallelism of the opposite walls of each groove in the direction of the thickness of the plate—that is to say, in the direction of the height of the said walls—renders the grooving process less difficult and expensive than would be the case if the grooves were dovetailed or otherwise undercut. It also enables a block with its parts, including the catch, assembled and connected together to be inserted into a groove or removed therefrom at any point by simply a vertical movement when the block is in its collapsed condition. The described construction of the clamp-blocks enables the same to be made of comparatively small thickness, permitting the grooves 2 2 to be made comparatively narrow, so as thereby to leave between them portions of considerable width of the full height of the block to afford complete support for the plate A.

A characteristic of the construction which is described and shown herein is the fact that the members of a clamp are joined together in assembled condition, so that the clamp may be handled as a whole. This adds greatly to the convenience with which the clamp may be used in practice, since the members thereof do not tend to become separated and lost, no time is required to be expended in assembling the said members when it is desired to apply the clamps to the block 1, and when it is required to change the clamp from one groove to another all that is necessary is to loosen the screw 6, so as to permit the clamp-block to be contracted in thickness, after which the clamp in its entirety may be lifted up and transferred to the

other groove, the block 3 4 in contracted condition lifting readily out of the groove in which the same is first contained and slipping down into place in the other groove.

5 I claim as my invention—

1. The combination with a grooved plate-supporting block, of a holder for electrotype-plates and the like, having a top portion which engages the electrotype-plate, a body portion making contact with one wall of the groove in which it is placed and provided with laterally-projecting end flanges, an expanding member movable vertically between said end flanges and making contact with the other wall of said groove, and a screw passing through a hole in said top portion and in screw-thread engagement with said expanding member.

2. In a holder for electrotype-plates and the like, for use in printing, the combination with a plate-supporting block provided with grooves having parallel vertical walls, of a clamp comprising a plate-engaging member, having a flat lower face, and a clamp-block consisting of two relatively movable members having outer surfaces which are parallel with each other, to make frictional engagement with the parallel side walls of a groove in said plate-supporting block, and adjacent inclined surfaces, and operating means to force the plate-engaging member into contact with the plate to be held and expand the clamp-block in its groove.

3. In a holder for electrotype-plates and the like, for use in printing, the combination with a plate-supporting block provided with grooves having parallel vertical walls, of a clamp comprising a plate-engaging member, having a flat lower face, and a clamp-block consisting of two relatively movable members having outer surfaces which are parallel with each other, to make frictional engagement with the parallel side walls of a groove in said plate-supporting block, and adjacent inclined surfaces, and operating means to force the plate-engaging member into contact with the plate to be held and expand the clamp-block in its groove, one member of said clamp-block having end flanges embracing the other member of said block.

4. In a holder for electrotype-plates and the like, for use in printing, the combination with a plate-supporting block provided with grooves having parallel vertical walls, of a clamp comprising a plate-engaging member and a clamp-block consisting of two relatively movable members having outer surfaces which are parallel with each other, to make frictional engagement with the parallel side walls of a groove in said plate-supporting block, and adjacent inclined surfaces, and a screw passing through said plate-engaging member and tapped in one member of said clamp-block, to force the plate-engaging

member into contact with the plate to be held and expand the clamp-block in its groove.

5. In a holder for electrotype-plates and the like, for use in printing, the combination with a plate-supporting block provided with grooves having parallel vertical walls, of a clamp comprising a plate-engaging member and a clamp-block consisting of two relatively movable members having outer surfaces which are parallel with each other, to make frictional engagement with the parallel side walls of a groove in said plate-supporting block, and adjacent inclined surfaces, and a screw passing through said plate-engaging member and tapped in one member of said clamp-block, to force the plate-engaging member into contact with the plate to be held and expand the clamp-block in its groove, one member of said clamp-block having end flanges embracing the other member of said block.

6. In a holder for electrotype-plates and the like, for use in printing, the combination with a plate-supporting block provided with grooves, of clamps each of which comprises a plate-engaging member, having a flat lower face, and a clamp-block consisting of two relatively movable members having adjacent inclined surfaces, and a screw passing through said plate-engaging member and tapped in one member of said clamp-block, and serving to force the plate-engaging member into contact with the plate to be held and expand the clamp-block in its groove.

7. In a holder for electrotype-plates and the like, for use in printing, the combination with a plate-supporting block provided with grooves, of clamps each of which comprises a plate-engaging member, having a flat lower face, and a clamp-block consisting of two relatively movable members having adjacent inclined surfaces, and operating means to force the plate-engaging member into contact with the plate to be held and expand the clamp-block in its groove.

8. A plate-holder of the character described, comprising a base or block provided with slots, and plate-holding clamps arranged on said block, said clamps consisting of a plate, a screw upon which said plate is mounted to turn, a laterally-movable clamping member coöperating with a wall of said slot and independent of said plate to permit said plate to be turned on said screw after said clamping member is inserted in said slot, and means movable longitudinally on said screw and coöperating with said laterally-movable member to move the same into engagement with the wall of said slot.

9. A plate-holding clamp for plate-holders of the character described, consisting of a plate, a screw upon which said plate is mounted to turn, a nut movable longitudi-

nally on said screw and provided with an inclined surface, and a coöperating clamping member having an inclined surface which coöperates with the inclined surface of said 5 nut, said clamping member being separate from said plate and moved laterally by movement of the nut on said screw.

In testimony whereof I affix my signature in presence of two witnesses.

FRITHEOF H. HOFFSTEDT.
